UNITED STATES PATENT OFFICE.

CHARLES A. MEADOWS, OF YONKERS, NEW YORK, ASSIGNOR TO MERCHANTS PRINTING AND MANUFACTURING COMPANY, OF YONKERS, NEW YORK, A CORPORATION OF NEW YORK.

PAPER BAG OR ENVELOP.

No. 824,878.

Specification of Letters Patent.

Patented July 3, 1906.

Application filed November 16, 1904. Serial No. 232,924

To all whom it may concern:

Be it known that I, CHARLES A. MEADOWS, a citizen of the United States, residing at Yonkers, in the county of Westchester and State of New York, have invented certain new and useful Improvements in Paper Bags or Envelops, of which the following is a specification, reference being had to the drawings accompanying and forming part of the same.

10 My invention relates to paper-receptacles in the form of a bag or envelop, and has for its object to provide an article of this kind which may be readily opened after being sealed and which may then be spread out 15 into a sheet.

The envelop-blank may bear printed or other characters on its inner as well as on its outer surface, so that upon opening the envelop the printed matter thereon is presented 20 conveniently for reading. The device therefore serves not only as a readily-opened envelop or container for transmission through the mails or otherwise, but also as a circular or folder upon which advertising or other matter may be placed.

A further object of the invention is to provide a bag or envelop in which the mouth or opening through which the contents of the envelop are inserted is "expansible"—that 30 is, may be expanded to a larger size than normal for the purpose of readier insertion of the merchandise or other contents, and then contracted wholly or partially to its normal size before being closed by the flap or other closing device. This expansible feature greatly facilitates the insertion of the contents of the bag, and where large numbers of them are used, as for "pay-envelops" for sending out samples, &c., the economy of time and labor 35 40 thus secured becomes a considerable item.

A further object is to provide means for readily opening the envelop, applicable not only to the specific article herein described, but also in general to envelops or bags made 45 of material which can be severed by tearing.

Another object of the invention is to provide an article embodying the features described above, which shall be as simple as possible in construction, and therefore inexpensive to manufacture.

The invention is capable of various embodiments; but I have shown only the pre-

ferred form in the accompanying drawings, in which—

Figure 1 shows the blank from which the envelop is made, the surface presented to the view being that which is afterward the outer surface of the envelop. Fig. 2 shows the completed envelop with its filling-opening expanded. Fig. 3 shows the circular or 60 folder produced by opening the envelop. Fig. 4 is a detail view showing the preferred location of the perforations in the flap which closes the mouth or filling-opening of the bag relative to the line of fold of the said flap. Fig. 65 5 is a section on line V V of Fig. 4. Fig. 6 is a plan view of the mouth of the envelop illustrated in Figs. 4 and 5, showing the form assumed by the mouth when the side edges of the envelop are compressed.

In the preferred embodiment of my invention I use a blank 1 of a general square or rectangular shape, having on opposite sides and near the center flaps 2 3. One corner of the blank is provided with a projection or tab 4. 75

In the completed bag, the end bearing the tab 4 (or either end, if each has a tab) is folded upon the central portion of the blank along the lines *a b*, and upon this is folded the other end along the line *c d*. The flap 3 is 80 then folded over, not, however, along a line close to the edges of the folded ends of the blank, but on a line removed from these edges an amount equal to or greater than the height of the tab 4, as indicated by the line *e f*. The 85 flap 3 is then sealed down, and in so doing the inner tab 4 may be caught by the gum or glue on the flap. The inner body-flap carrying the tab is thereby fastened at its innermost corner to the end flap 3, thus preventing the said body-flap from being wholly withdrawn from its folded position. In this way the blank is made into a bag or envelop, as shown in Fig. 2. The body-flaps are unattached at their upper ends, so that they 95 may be opened out to a certain extent, thus enlarging or "expanding" the mouth of the bag, as shown. When the contents of the envelop have been inserted, the mouth contracts or may be contracted wholly or partially to its normal size, and the sealing-flap 2 is then glued down upon the outermost body-flap.

From an inspection of Fig. 2 it will be evi-

dent that if the end flap 2 be severed access may be had to the contents of the envelop, which still retains its character as a bag or container and may be utilized as such, as is often desirable; but upon severing the other end flap also the envelop may be opened out into a perfectly flat sheet, revealing the matter written or printed on the inner surface. For the purpose of severing the flaps they may be perforated along the proper lines, and in order to tear the same readily and quickly I prefer to employ a severing string or wire threaded through the perforations. A convenient method is to sew a thread along the tearing-line, leaving one or both ends of the thread projecting, which may be grasped and pulled, thereby tearing the paper and releasing the flaps. This method possesses another advantage in that the tab 4 may be fastened to the flap by this line of stitching, thus making it unnecessary to secure the tab by gum. The severing of the flap by pulling the thread will of course release the tab at the same time. The provision of a tearing-string obviates danger of injury to the contents of the envelop in opening the same, as might happen if the perforations were located a sufficient distance from the edge to make a tearing-strip wide enough to be grasped by the fingers. In such case if no severing-string were used the contents of the bag might extend beyond the perforations toward the edge, and so be grasped and torn with the tearing-strip. The stitching or severing string also reinforces the edge of the envelop and greatly increases its resistance to tearing across the edge, since before the paper can be torn downward across the edge the string itself must be broken.

A more convenient arrangement for grasping the tearing-thread is shown in Figs. 1 and 2. Each flap 2 or 3 is provided on the line of its fold with an opening, as 5, so that when folded down a portion of the thread intermediate to its ends is wholly exposed, as shown at 6, Fig. 2, and thus may be readily grasped and pulled to open the envelop. The stitching in the case of flap 2 may be either along its line of fold, as shown in Fig. 2, or between the fold and the edges of the body-flaps, as shown in Figs. 4, 5, and 6. I prefer to stitch flap 2 not on the line of fold, but between the fold and the edges of the body-flaps. This method is more economical in the labor of manufacture, as with the flap folded down the envelop can run through the sewing-machine very rapidly, the folded edge being merely held against a guide to make the row of stitches of uniform distance from said edge, whereas to sew the flap on the line of fold necessitates sewing before the flap is folded, while it is flat. Some care is then necessary to make the stitching straight and accurate. Furthermore, the form shown in Figs. 4 and 5 possesses an advantage in the

fact that when the flap 2 is opened the stitching and double thickness of the fold constitute a strengthening-rib, while the tearing-aperture 5 acts as a hinge, causing the bend to occur at that point, as indicated in Fig. 6. 70 This construction to a considerable degree facilitates the insertion of the contents of the envelop, since the mouth may be readily opened merely by compressing the side edge of the envelop. In the other flap 3 the stitching should be between the fold and the edges of the body-flaps, so as to engage the tab 4, as shown in dotted lines in Fig. 3. In the construction just described the ends of the threads need not be left projecting, but may 80 be cut off close to the edge of the bag. It is obvious that this arrangement for opening a bag or envelop is not confined to use in connection with that herein shown, but is of general applicability to bags or envelops made 85 of material which may be severed by tearing.

In the form shown in Fig. 2 the perforation or stitching of the flap 3 was effected after the flap is folded down and gummed in position; but it is obvious that the stitching 90 may be done before folding, as in the case of flap 2, care being taken that the tab 4 is sewed to the flap. The latter may then be folded along the line of stitching, as is done in the case of flap 2 in Fig. 2, or in a line slightly removed therefrom. The stitching, the crease, and the grasping-opening in each flap should, however, register closely enough to enable the thread or wire to be readily seized, as shown in Fig. 2. 100

It will be noted that in Fig. 1 the advertisement or other reading matter is not "complete"—that is, it ends without completing the sense of the article or without giving all the information that it is very evidently 105 meant to convey. On the inner surface, however, the article or advertisement is completed. The reader thus has an incentive to tear open the envelop to see what is on the inside. At the end of the matter on the outer side a sentence may be added, as shown in Fig. 1, explaining how access may be had to the reading matter on the inside. Of course pictures may be substituted for reading matter, or both reading matter and pictures may 115 be used, as desired.

Having now described my invention, what I claim is—

1. As a new article of manufacture, a bag or envelop comprising a body portion having 120 side or body flaps folded one upon the other and unsecured along their sides, and end flaps one of which constitutes the closure for the envelop, the other end flap and the side or body flaps being secured together and provided with means for severing the end flap and simultaneously releasing the side or body flaps, the closure end flap being adapted to be sealed to the outer side or body flap and provided with means for severing the folded 125 130

edge from the sealed portion, whereby when the ends of the sealed envelop are severed the side or body flaps are free to be unfolded and with the body portion form a flat sheet, as set forth.

2. As a new article of manufacture, a bag or envelop having body-flaps folded one upon the other, the inner body-flap having a tab or projection extending beyond the adjacent edge of the outer body-flap, an end flap folded upon the body-flaps, having a line of stitching engaging the tab on the inner body-flap, the thread of said stitching being adapted to be grasped and pulled to sever the end flap and tab, a second end flap adapted to be folded upon the body-flaps and to be secured to the outer body-flap, and means for severing the said second end flap; whereby severing the end flaps enables the bag or envelop to be opened as a sheet, as set forth.

3. As a new article of manufacture, a bag or envelop having body-flaps folded one upon the other, the inner body-flap having a tab or projection extending beyond the adjacent edge of the outer body-flap, an end flap folded upon the body-flaps having an opening in its line of fold and a line of stitching engaging the tab on the inner flap and extending across the said opening, a second end flap adapted to be folded upon the body-flaps and to be secured to the outer body-flap, said second end flap having an opening in its line of fold and a line of stitching extending across its opening; whereby the threads of the stitchings may be grasped where exposed by the said openings, as set forth.
